UNITED STATES PATENT OFFICE

ALVER H. McDONALD, OF ATLANTA, GEORGIA

SOCK SUPPORTER

Application filed September 22, 1932. Serial No. 634,401.

This invention relates to supporting means and more particularly to a supporting means for holding socks or the like in desired position on the limb of the wearer.

5 An object of this invention is to provide a device of this kind which is so constructed that it will be disposed beneath the article so that it will be hidden thereby, and which will so engage the limb of the wearer that it 10 will maintain the article under desired tension at all times.

A further object of this invention is to provide an article supporting means which will not unduly bind on the limb of the wearer and which will not readily slip down so as to permit the article supported thereby to become loosened.

A still further object of this invention is to provide a device of this kind which can be 20 readily mounted and removed from the limb of the wearer.

The above and various other objects and advantages of this invention will in part be described and in part be understood from the 25 following detailed description of the present preferred embodiment, the same being illustrated in the accompanying drawing wherein:

Figure 1 is a detail rear elevation of a limb 30 having a device constructed according to the preferred embodiment of this invention mounted thereon and showing the sock or article partly broken away;

Figure 2 is a fragmentary enlarged vertical section taken on the line 2-2 of Figure 1;

Figure 3 is an enlarged rear elevation of the upper portion of the device showing the manner of mounting the garment supporter 40 on the upper end of the supporting member;

Figure 4 is an enlarged sectional view taken on the line 4-4 of Figure 1; and

Figure 5 is an enlarged sectional view taken on the line 5-5 of Figure 1.

45 Referring to the drawing wherein like numerals of reference designate corresponding parts throughout the several views, the letter L designates generally a limb or leg of an individual, which has mounted thereon 50 a sock or article S of desired length,

which in the present instance is shorter than the leg L and of a type used by men.

In order to support the sock S on a limb L without unduly binding the limb at a point above the calf of the limb, I have provided 55 a supporting means including an elongated member, generally designated as 10, which is constructed in the form of a flat bar of resilient construction, which has a degree of rigidity and a degree of resiliency. This bar 60 or member 10 may be constructed of either metal or other material such as composition or the like.

The standard or supporting member 10 is provided at a point upwardly from the lower 65 end thereof with spaced slots 13 which are disposed in parallel relation to each other and through these slots a securing band 11 is passed. This band 11 is of elastic construction so that it can be readily slipped 70 over the heel or the limb L and one end of the band or securing member 11 is provided with a clip 12 so as to prevent the fraying of the end of the band and also provide means whereby the free end may be pulled so as to 75 tighten the securing member 11 about the limb L.

This band 11 is mounted at a point upwardly from the ankle A of the limb L and any tension or strain applied to the member 10, 80 will have a tendency to expand the band 11 which, due to its elasticity, will resiliently resist such downward movement of the supporting member 10. The lower end of the vertical supporting member 10 is provided 85 with a pair of wings 14 which are adapted to engage on opposite sides of the tendon of the limb L so that the vertical member 10 will be thereby held against circumferential movement upon the limb L.

The upper end of the elongated supporting member 10 is provided with a headed pin 15 which extends through the supporting member 10 and is secured to a plate 16, mounted 90 on the inner surface of the member 10.

A flexible strap 17 is secured to the upper end of the plate 16 and engages over the top of the supporting member 10 and has a loop 18 attached thereto which is adapted to engage over the pin 15 in a well known man- 100

ner so as to bind the upper end portion of the sock S about the pin 15. This loop 18 has a restricted end portion 19 within which the pin 15 is adapted to engage and bind the sock 5 about the head of the pin 15.

In the use of this device, the supporter comprising the vertical member 10 and the loop 11, is adapted to be mounted upon the limb L with the loop or securing band 11 positioned at a point slightly above the ankle 10 A. The sock S may then be drawn onto the limb L and the upper end portion of the sock engaged over the pin 15.

The loop 18 is then slipped over the pin 15. 15 The entire supporting means is disposed beneath the sock S and any tendency of the sock S to pull the supporting member 10 downwardly will be resisted by the elastic strap 11. The wings 14 which engage one on 20 each side of the tendon of the leg will prevent circumferential movement of the band 11 and also of the supporting member 10. Furthermore, by positioning the band 11 at a point above the lower end of the supporting member 25 10, the supporting member will be held in vertical position more readily on account of the wings 14 holding the lower end of this supporting member 10 against lateral or circumferential movement. This member 10 30 may be, as heretofore stated, constructed out of either metal or composition of material and may be suitably covered with a shield or the like so as to prevent contact of any metal or the like with the limb L. 35 It is, of course, understood that various changes and modifications may be made in the details of construction and design of the above specifically described embodiment of this invention without departing from the 40 spirit thereof, such changes and modifications

being restricted only by the scope of the following claims.

What is claimed is:—

1. A supporter comprising an elongated resilient member having slots positioned adjacent one end thereof, an elastic loop engaging in said slots, a securing means carried by the other end of the member and means carried by said one end and extending below the slots to hold the member against circumferential movement on a leg, said latter means also co-acting with the loop in holding the member in upright position. 70

2. A supporter comprising an elongated resilient member having slots disposed at a point adjacent one end thereof, an elastic loop extending through said slots and adapted to engage about the leg at a point upwardly from the ankle, a securing means carried by the other end of the member and a pair of 80 wings carried by said one end of the member and engaging one on each side of the tendon of the leg to hold the member against circumferential movement on the leg. 85

3. A supporter comprising an elongated resilient member having a pair of slots disposed adjacent one end, an elastic loop engaging in said slots and adapted to engage about the limb of a wearer at a point above the ankle of the limb, a securing means carried 90 by the other end of the member to secure an article on said other end and a pair of wings carried by said one end of the member and disposed in downwardly divergent relation 95 and engaging on opposite sides of the tendon 100 of the limb to hold the member against circumferential movement on the limb.

In testimony whereof I hereunto affix my signature.

ALVER H. McDONALD. 105
